CLAIM

The ornamental design for a low rider bicycle frame, as shown and described.

DESCRIPTION

FIG. 1 is a side view of the low rider bicycle frame, showing my new design;

FIG. 2 is a top plan view thereof;

FIG. 3 is a bottom elevational view thereof;

FIG. 4 is a front elevational view thereof; and,

FIG. 5 is a rear, elevational view, thereof.

The portions of the bicycle shown in broken lines in FIG. 1 are for illustrative purposes only and form no part of the claimed design.

1 Claim, 1 Drawing Sheet5.5

FIG. 4

FIG. 2

The diagram illustrates a double-walled tube assembly. It consists of an outer tube and an inner tube. The inner tube is positioned such that its open ends are at the top and bottom. A central channel runs vertically through the tube. A side port, indicated by a small circle with a line, is located on the outer wall of the inner tube, positioned roughly one-third of the way from the top. The tube is shown in perspective, with the top and bottom ends cut away to reveal the internal structure.

FIG. 2
